THEATER CHAIR

Filed Aug. 1, 1923

Inventor

John Paul Satterlee

Patented Nov. 15, 1927.

UNITED STATES PATENT OFFICE.

JOHN PAUL SATTERLEE, OF KLAMATH FALLS, OREGON.

THEATER CHAIR.

Application filed August 1, 1923. Serial No. 655,044.

My invention relates to a theatre chair and the main objects to be accomplished are:

1. To construct a retracting gravity operated chair which will permit by the action 5 of the occupant of increased space being formed at will between himself and other objects or chairs in front and thus permit free passage through a wider aisle for any 10 passer-by without the necessity of the seat occupant rising.

2. To bring about the locking and holding of all movable parts of the chair when the seat is thrown up into a vertical position.

15 3. To bring about the construction and operation of a chair of the type described with arms which will rise and move with the seat and back when the chair is operated.

I attain these objects by the mechanism 20 illustrated in the following drawing in which Figure (1) is a side view of the chair, the nearest standard being removed, thus exposing side panels and seat with supporting mechanism, showing seat and back with 25 attached parts in two positions, namely the normal and the retracted one.

Figure 2, is a sectional front view taken on line 2—2 of Figure 1.

Figure (3), is a side view of chair showing 30 nearest standard and side panel with attached parts to same removed and the position of seat and parts when said seat is in a vertical position to clear aisle and lock chair.

35 Similar letters refer to similar parts throughout the several views.

The standards SS the back; the studs BB and *xx*; the seat G with grooved ribs MM together with the supporting side panels PP with attached pivot hinge mechanism and inclined guides XX at the tops constitute 40 the principal parts of the chair. The occupant placing himself on seat G is in a normal resting position, the weight of his body being in part carried by roller bearings *bb* traveling in grooves *gg* in side members MM, which rollers are journaled on studs BB attached to standards: also in part by pivot hinges *hh* in side panels PP which 45 panels have inclined guides resting on roller bearings *zz* at the top back extremities of standards SS.

50 Desiring to retract the chair and widen the aisle, the occupant of the chair places his feet on the floor and by a backward motion 55 of the body pushes the chair seat, together

with the supporting side panels and the attached back to the rear until at any point desired this action is checked by the outward flanged front edges of panels PP as 60 shown by dotted line near X in Figure (1), striking stops CC on standards SS. This action is brought about by the suspended side panels PP rolling on guides XX over rollers *zz* and supported seat G rolling on 65 guides *gg* over rollers *bb*, the guides XX and grooves *gg* being of any inclination desired but adjusted to the same pitch or slope.

When no upward thrust is exerted at the 70 free or forward edge of the seat, the same is permitted to be shifted rearwardly freely and without binding of the inwardly extending flanges at the lower sides of the grooves or channels *gg* of the seat supporting members MM against the rollers *bb*. To avoid any upward movement of the seat about the pivot hinges *hh*, which movement would interfere with the free rearward shifting of the seat, I have provided a catch 75 or latch member L which is pivoted at its one end on one of the side or seat supporting members M, said latch member being normally retained, by means of a spring, with its opposite or free end, when the seat 80 is shifted to its extreme forward position, in engagement with one of the rollers *b*, as shown in Figures 1 and 2, the roller in Figure 1 being removed to facilitate the illustration. As the seat is shifted inwardly or 85 rearwardly by the occupant, the latch member is rotated about its axis by the spring by reason of the disengagement of the free end of the latch member from the roller, permitting an inwardly turned lug near the 90 pivot portion of the latch member to engage a recess portion in one of the members secured over the inner sides of the side members MM, as shown best by dotted lines in Fig. 1. Said inwardly turned lug of the 95 latch member engaging said recess prevents the side or seat supporting members MM, and therefore the seat G, from being raised to any extent. When the seat is shifted forwardly, the free end of the latch member 100 engages the roller *bb* rotating the former, disengaging the inwardly turned lug thereof from said recess portion, and permitting the seat G to be rotated about its pivotal axis at *hh*.

105 It will be here noted, however, that the seat is prevented from being shifted upwardly by the flanges at the lower sides of

the grooves or channels *g* engaging the rollers *bb* as soon as the seat is shifted rearwardly a slight distance, but said flanges and rollers do not permit free rearward shifting of the seat when an upward thrust is produced at its free edge, said rearward shifting being permitted at all times only by said latch.

The occupant next, desiring to resume a normal position of the chair, relaxes his body and gravitational force acting through the downward inclination of the guides *XX* on rollers *zz* and also in grooves *gg* on rollers *bb* will force the seat and occupant forward until checked in a proper normal position by stops *oo* attached to side panels *PP* and impinging on absorbers made part of studs *BB*. By adjustment of the pitch of guides *XX* on side panels *PP* and that of grooves *gg* in side members *MM* in unison, this gravity action can be made more or less as desired.

To lock and hold all movable parts of the chair when seat *G* is thrown up in clear about hinges *hh*, circular grooves *nn* are made in ribs *MM*, which as seat *G* is revolved about hinge bolts *hh* moves on the studs *BB* locking seat, back, panels, and other parts in a forward position.

30 The following is claimed:

1. In a chair, a pair of spaced apart pedestals, side panels positioned between and adjacent the inner sides of said pedestals, extending from near their middle portions to near their upper ends, and shiftable relatively thereto, and roller means at the upper ends of said side panels in connection with said pedestals for supporting said panels on and for facilitating forward and rearward shifting of the panels relative to said pedestals.

2. In a chair, a pair of spaced apart pedestals, side panels positioned between and adjacent the inner sides of said pedestals and shiftable relatively thereto, and single roller means at both the upper and lower ends of each of said side panels in connection with said pedestals for supporting said panels on and for facilitating forward and rearward shifting of the panels relative to said pedestals.

3. In a chair, a pair of spaced apart pedestals, side panels positioned between and adjacent the inner sides of said pedestals, extending from near their middle portions to near their upper ends, and shiftable relatively thereto, and roller and inclined track means at the upper ends of said side panels and said pedestals providing roller suspension means for said side panels from said pedestals to facilitate forward and rearward shifting of the panels relative to said pedestals.

4. In a chair, a pair of spaced apart pedestals, side panels positioned between and

adjacent the inner sides of said pedestals and shiftable relatively thereto, single rollers revolvably mounted at the inner sides and near both the upper and lower ends of said pedestals, and inclined channel-shaped tracks provided near the upper and lower ends of said panels adapted to straddle and ride on said rollers.

5. In a chair, a supporting means, a pair of spaced apart side panels shiftable mounted relatively to said supporting means, a seat positioned between said side panels and provided with a pair of spaced apart downwardly extending seat supporting members, said seat supporting members being pivotally mounted near the lower ends of said side panels and provided with forwardly and downwardly extending tracks, roller means mounted on said supporting means and adapted to engage the tracks on said seat supporting members, and a latch pivotally mounted on one of said seat supporting members and adapted to engage the roller of said roller means when the seat is in a forward position and adapted to engage an inwardly extending portion of one of said side panels when the seat is shifted backwardly to prevent the upward raising of the same.

6. In a chair, a supporting means, a seat and side panels shiftable supported on said supporting means, bearing roller means mounted on the lower portions of said supporting means, track means carried by the lower portions of said side panels and adapted to ride on said roller means, suspension roller means mounted on the supporting means near the upper ends thereof and positioned backwardly from said bearing roller means, and other track means carried by the upper portions of said side panels and adapted to ride on said suspension roller means.

7. In a chair, a supporting means, side panels shiftable supported on said supporting means, a seat pivotally mounted between said side panels, bearing roller means mounted on the lower portions of said supporting means, track means carried by the lower portions of said side panels and adapted to ride on said roller means, suspension roller means mounted on the supporting means near the upper ends thereof and positioned backwardly from said bearing roller means, other track means carried by the upper portions of said side panels and adapted to ride on said suspension roller means, and means in connection with said seat and the lower roller means to prevent inward shifting of said seat when the same is in a raised position.

8. In a chair, a supporting means, side panels shiftable supported on said supporting means, a seat pivotally mounted between said side panels, bearing roller means mounted on the lower portions of said supporting means, track means carried by the lower portions of said side panels and adapted to ride

on said roller means, suspension roller means mounted on the supporting means near the upper ends thereof and positioned backwardly from said bearing roller means, other track means carried by the upper portions of said side panels and adapted to ride on said suspension roller means, and pivotal latch means in connection with said seat adapted to normally engage one of the lower roller means when said seat is shifted forwardly and to be disengaged therefrom when said seat is shifted backwardly, whereby said seat is prevented from being raised when the same is shifted backwardly.

9. In an auditorium aisle chair, a pedestal having a downwardly and forwardly inclined upper edge, a side panel shiftably mounted on one side of said pedestal and provided at its upper end with an arm supporting member, said arm supporting mem-

ber being provided on its under side with a groove conforming in inclination and shape with the upper edge of said pedestal and adapted to receive the same.

10. In a chair, a supporting means, side panels supported by said supporting means and shiftable rearwardly and forwardly relative thereto, a seat and a back supported by and between said side panels, said seat being foldable relative to said back, and means for locking said back and said seat in unfolded relation when shifting said panels rearwardly, said locking means being released when said panels are shifted to their forward positions to permit said seat to be folded upwardly, said panels being locked in their forward positions when said seat is folded upwardly.

In testimony whereof I affix my signature.
JOHN PAUL SATTERLEE.
